CLAIM

The ornamental design for a pack for smoking articles, as shown and described.

DESCRIPTION

FIG. 1 is a perspective view of the pack in closed position embodying the new design;

FIG. 2 is a rear perspective view of the pack in closed position;

FIG. 3 is a front perspective view of the pack in an open position;

FIG. 4 is a rear perspective view of the pack in an open position;

FIG. 5 is a top face of the pack;

FIG. 6 is a left side face of the pack;

FIG. 7 is a front face of the pack;

FIG. 8 is a right side face of the pack;

FIG. 9 is a back face of the pack; and,

FIG. 10 is a bottom face of the pack.

In FIGS. 3 and 4, the portions of the pack that are hidden by the cover form no part of the claimed design.
